LEVEE-BUILDING MACHINE.

No. 852,791.

Specification of Letters Patent.

Patented May 7, 1907.

Application filed August 31, 1906. Serial No. 332,831.

To all whom it may concern:

Be it known that I, CHARLES C. JACOBS, a citizen of the United States, residing at Chicago, in the county of Cook and State of Illinois, have invented certain new and useful Improvements in Levee-Building Machines, of which the following is a specification.

My present invention concerns levee building machines or trench excavators and its principal object is the production of such a machine whose frame shall be of simple character, of as light weight as is consistent with the strength required, and one which can be easily taken apart, transported and reassembled.

Another object of my invention is the production of a structure which is largely if not entirely balanced whereby a comparatively small and inexpensive main frame may be used. This main or supporting frame is caused to rest upon and ride on temporary rails laid upon the strip of ground between the base of the levee and the adjacent edge of the ditch or trench from which the earth is excavated to form the dike or levee. Hinged to the trench end of this main frame is a ditch track section adjustable up and down and shaped to conform substantially to the cross-sectional profile or outline of the trench to be dug, and fastened to the opposite end of the frame is a dumping or discharge track section adapted to overhang the levee. The center or main frame is equipped with a steam engine and boiler and a track section forming a connection between the ditch and levee or dumping track sections, one or more sharp-edged excavating shovels being adapted to travel on the track sections to remove dirt from the trench, convey it through or across the main frame, and discharge it upon the gradually forming levee. The engine is used to traverse the shovel or shovels back and forth, to raise or lower the adjustable ditch track section, and to cause the whole frame to move longitudinally of the trench or levee when it becomes necessary to excavate a new portion of ground or build a new section of the levee.

In the accompanying drawings I have illustrated the preferred embodiment of my invention, like reference characters referring to the same parts throughout the various views.

Figure 1 is a side elevation of my improved balanced levee builder or trench excavator:

Fig. 2 is an enlarged side elevation of the central portion of my improved machine; Fig. 3 is a plan of the machine, certain parts being broken away; Fig. 4 is a view on a reduced scale of the right-hand elevation of the fragmentary structure illustrated in Fig. 2; Fig. 5 is a view showing the excavating shovel, the trackway and associated parts; and Fig. 6 is a section of the shovel or track on line 6—6 of Fig. 5.

My new type of machine comprises a main or intermediate frame 10, adapted to travel on the bank between the levee and trench, having hinged at one end a ditch track section 11, and having hinged at the opposite end a discharge or dumping track section 12, both of these sections being adjustable vertically as set forth hereinafter. The main frame 10 is provided with two longitudinal sills 13 each composed of a pair of spaced channel bars 14. On the under sides of these sills I rotatably mount in suitable bearings a number of wheels or rollers 15 adapted to travel on temporary rails 16 spiked to the top surfaces of temporary beams 17 laid on the ground between the positions of the levee to be built and the trench to be dug. Above these longitudinal sills or beams 13 and cross-connecting the same are a plurality of transverse beams 18 which support the floor 19. To two adjacent cross-beams 18 are fastened a pair of upright frame sections 20 of substantially A-shape, the top ends of which are tied together by angle bars 21. Inside of these A-frame members is a pair of built up frames or trusses 22 which support angle bars 23 forming the track section of the main frame.

At the right-hand end of frames 22, as viewed in Figs. 1 and 2, and at the end of the track angle bars 23 at the points 24 is pivoted or hinged the ditch track section supporting frame 11. This frame includes a pair of bent plates 25 shaped to conform substantially to the cross-sectional profile of the trench to be dug. These plates 25 are of somewhat U-shape, the upper ends of their legs being joined by the bars 26, while additional bars 27 and 28 stiffen the structure and prevent bending or deflection of the track plates. On the inner side of each of the track plates 25 are secured upper and lower angle bars 29 and 30, upon the former of which the wheels of a shovel truck travel, while angle bars 30

keep the shovel down to its work and prevent it from rising. Plates 25 are maintained spaced apart the proper distance by upwardly projecting frames 31 cross-connected 5 at their tops by suitable lattice work.

Hinged at 32 on the same end of the main frame 10 above hinges 24 are a pair of channel supporting bars 33 whose upper ends are sustained at the proper elevation by means 10 of one or more cables 34 connected to the tops of A-frames 20.

Hinged to the opposite end of frames or trusses 22 at the other ends of track angle bars 23 are two plates 35 supplied with upper and lower track angle bars 36 and 37 similar to the angle bars 29 and 30. These two plates 35 with their angle bars form the dumping or discharge track section, the outer end of which is supported by one or more cables 38 also connected to the tops of A-frames 20 and adjustable by means of turn-buckle 38^a. In order to keep the plates 35 spaced apart the proper distance they are each equipped with a light framework 39 20 cross-connected and latticed together.

It is to be understood that one or more sharp-edged dumping shovels shall reciprocate on the three track sections forming in reality a single trackway. In the present 30 device I have illustrated only one of such shovels by way of example. Its truck comprises the side channel bars 40 [Figs. 5 and 6] tied together at their front ends by angle bars 41 to which is secured means 42 for the attachment of an advancing cable 43. In addition to the angle bars 41 a channel bar 44 also spaces apart channels 40 which at their rear ends are maintained apart by angle bars 45. This truck is supplied with the forward 40 and rear axles 46 and 47 each of which has two flanged rollers or wheels 48 adapted to travel on the angle bars of the track sections. Pivoted on the rear axle 47 and extending forwardly with their top flanges overlapping 45 the top flanges of channels 40 are a pair of angle bars 49 to the downwardly depending legs of which are riveted a pair of supporting plates 50 in which is mounted the shaft 51 with or upon which the sharp-edged shovel 52 is adapted to turn, as indicated in dotted lines in Fig. 5. This shovel 52 has an open forward mouth 53 having a lower sharp cutting edge 54, while the rear portion of the bucket curves toward its top as at 55. The 55 pivotal point of the bucket is such that when released the bucket or shovel will normally turn so as to discharge its load out of its open mouth. Extending across the top of this shovel or scoop is a bar 56 provided with means 57 for the attachment of a shovel righting and retracting cable 58. In order to maintain the bucket or scoop 52 in load retaining position there is provided two catches 59 which under normal conditions 60 are projected above the rear upper edge of

the shovel by means of an elliptic spring 60 inserted between the rear angle bar 45 and a small angle bar 61 connecting the two catches 59, the latter being capable of reciprocation through apertures or slots in the angle bars 70 45. When thus thrust outwardly or into operative position by spring 60 the catches prevent the bucket from turning on its pivot 51. These catches may be tripped manually if desired by an operator located in the rigging 75 of the machine, but I prefer to retract them automatically and for this purpose employ a shaft 62 rotatably mounted in channels 40 and having one or more fingers 63 projecting in a slot or slots of catches 59. Shaft 62 is 80 also equipped with an arm 64 the turning of which causes the retraction of the catches thereby permitting the bucket under the influence of its load to turn about its pivot and discharge its lading. Suitably mounted at 85 any convenient point on the discharge track section is a transverse rod 65 upon which is pivotally mounted a trip arm 66, free to turn in one direction and prevented from rotation in the opposite direction by a fixed stop 67. 90 This trip arm 66 is so positioned that as the shovel ascends the discharge track section 35 it engages the arm 64 and pulls the catches backwardly whereby dumping of the bucket is effected. When the bucket and truck return in their downward movement on the track the arm 64 readily passes beneath the arm 66, the latter turning on its rod 65 sufficiently for this purpose. It is desirable to 95 reciprocate this bucket or shovel 52 back and forth on the trackway by power, to raise and lower the ditch track frame by the same source of power, and to use this same operating mechanism to traverse the whole excavator or levee builder along the temporary 100 rails 16, consequently I mount upon the platform of the main frame at one side of the A-frames 20 a steam boiler 68 which furnishes power for the operation of a steam engine 69 mounted above the track section of the main 105 frame on frames or supports 22.

The engine is supplied with two drums 70 and 71, the former of which winds up and pay out the shovel advancing cable 43, while the latter operates in like manner upon the shovel retracting cable 58. Cable 43 passes around a sheave or pulley 72 at the upper end of the discharge track section 35, while cable 58 passes around a similar sheave or pulley 73 at the outer end of the ditch track 110 section 11. In addition to these sheaves I provide along the trackway additional rollers or sheaves 74, 75, 76 and 77 with which both of the cables co-act as the shovel reciprocates. Engine 69 also operates another 115 drum 78 to wind up or pay out a cable 79 which controls the raising or lowering of the ditch track section, the latter turning about its hinges 24. Cable 79 passes around a sheave 80 at the top end of arms 33 then 120

125

130

passes downwardly around a pulley 81 supported by bars 28 of frame 11 thence upwardly once again around the sheave 80, downwardly around pulley 81, and then upwardly to the end of arms 33 where it is securely fastened.

In order to prevent the dirt spilling upon the level ground between the levee and the edge of the trench as the shovel travels through or across the main frame 10 I provide the latter with an apron or shield 82 having downwardly bent ends 83 and 84.

The whole frame may be made to travel along the temporary rails by means of the following named parts. The wheels 15 at one end of the frame are connected by a shaft 85, this shaft being supplied with a sprocket wheel 86 around which passes a sprocket chain 87, which in turn encircles a similar sprocket wheel 88 on a jack shaft 89 suitably mounted in bearings 90 and provided with a bevel gear 91. Another jack shaft 92 is caused to rotate by the engine through spur gears 93, and at the end of shaft 92 adjacent to shaft 89 is a loose bevel gear 94 meshing with gear 91, gear 94 being capable of rotating with shaft 92 when coupled therewith by the manually actuated clutch 95. It will be readily seen that, by operating this clutch 30 and the engine, the whole frame may be made to travel along longitudinally of the dike and trench so that a new section of the former may be built or by excavating earth forming an extension of the trench.

Assuming that the temporary rails have been properly laid, that the ditch track section has been elevated by cable 79 and overhangs an unexcavated portion of ground, while the dumping or discharge track section 40 35 has been adjusted to the proper elevation, the operation of the device is as follows: The ditch track section is allowed to descend by turning its hinges 24 sufficiently so that as the shovel moves forwardly it will shave off a layer of dirt, carry it through the main frame, spilling thereof being prevented by apron 82, and conveyed upwardly along the discharge track section until the shovel releasing arm 64 strikes the trip arm 66 whereupon catches 59 are retracted, the shovel turns on its pivot due to its load, and discharges the same to form a part of the dike or levee. During this advancing of the shovel on the trackway cable 43 is being wound 45 50 55 upon its drum 70 while cable 58 is paid out at a corresponding rate from drum 78. After the load of the shovel has been discharged, however, the operator of the device causes the drums to so turn that cable 58 will be 60 65 wound upon its drum and cable 43 paid out from its drum. As soon as the pull is exerted upon cable 58, it at once rights the shovel, the curved back portion of which 55 presses the catches inwardly until the shovel is fully righted when they spring outwardly above its

top rear edge under the influence of spring 60. Further winding up of cable 58 causes the shovel to travel backwardly along its trackway as will be readily understood. The ditch track section is then lowered a small amount by paying out cable 79 so that upon the next advance movement of the shovel a sufficient layer of earth will be shaved off and dumped upon the gradually forming dike. This operation is repeated as many times as is necessary and when the dike has been completed to the proper height, or the ditch excavated to the proper depth, as the case may be, cable 79 is wound upon its drum 78 so as to elevate the ditch track section 80 above the ground at which time the whole excavator can be made to travel along the temporary rails so as to bring its parts over a new section of ground to be excavated and its discharge boom in such position as to 85 form an additional section of the levee. This travel of the excavator is effected by the manipulation of clutch 95 thereby coupling the loose gear 94 to shaft 92 and through it causing the rotation of jack shaft 89. The 90 rotary motion of this latter shaft is transmitted to shaft 85 and two of the rollers or wheels of the frame through the sprocket chain 87 and its co-operating sprocket wheels 86 and 88. The operation of lowering the 95 ditch track section step by step is then repeated, the shovel reciprocating back and forth scraping out its load and discharging it upon the levee.

The main advantages of my improved excavator are its balanced construction whereby a small main frame is required and the ease with which its parts may be disassembled and reassembled to enable them to be transported on railway cars. The machine 100 105 may be used for the principal purpose of building the levee, or its main object may be the digging of the trench, and attention is directed to the fact that a trench of substantially twice the width of that illustrated may 110 be dug with an excavator of the type and size shown by first digging one section of the trench while the excavating machine travels along one bank and then digging an adjacent longitudinal section of the trench while the 115 excavator travels along its other bank.

Instead of digging the two longitudinal halves of the trench in succession by one device or simultaneously by two excavators, the single machine may be shifted laterally 120 of the trench so as to excavate two sections of the trench side by side before being moved lengthwise the ditch for further operations. Although I have shown this excavating mechanism in conjunction with a main frame 125 adapted to move along temporary rails it will be apparent to those skilled in the art that the device may be applied to a boat or scow for dredging purposes.

It is to be understood that various minor 130

mechanical changes may be made in the structure shown and described without departure from the heart and substance of my invention.

5 I claim:

1. In a machine of the character described, the combination of a main frame provided with a track section, a ditch track section secured to one end of said main frame, a dumping track section secured to the other end of said main frame, said track sections forming a continuous trackway, one or more sharp-edged shovels adapted to travel on said track sections, and means to operate said shovel or shovels, substantially as described.
2. In a machine of the character described, the combination of a main frame provided with a track section, a ditch track section secured to one end of said main frame and adapted to overhang the position to be occupied by the trench to be dug, a dumping track section secured to the other end of said main frame and adapted to overhang the position to be occupied by the levee to be built, said track sections forming a continuous trackway, one or more sharp-edged shovels adapted to travel on said track sections, and means to operate said shovel or shovels, substantially as described.
3. In a machine of the character described, the combination of a main frame provided with a track section, a ditch track section hinged to one end of said main frame, means to adjust the position of said ditch track section, a dumping track section secured to the other end of said main frame, said track sections forming a continuous trackway, one or more sharp-edged shovels adapted to travel on said track sections, and means to operate said shovel or shovels, substantially as described.
4. In a machine of the character described, the combination of a main frame provided with a track section, a ditch track section hinged to one end of said main frame, means to adjust the position of said ditch track section, a dumping track section hinged to the other end of said main frame, means to support the outer end of said dumping track section, said track sections forming a continuous trackway, one or more sharp-edged shovels adapted to travel on said track sections, and means to operate said shovel or shovels, substantially as described.
5. In a machine of the character described, the combination of a main frame provided with a track section, a ditch track section hinged to one end of said main frame, said ditch track section being shaped to conform substantially to the cross-sectional profile of the trench to be dug, means to adjust the position of said ditch track section, a dumping track section secured to the other end of said main frame, said track sections forming a

continuous trackway, one or more sharp-edged shovels adapted to travel on said track sections, and means to operate said shovel or shovels, substantially as described.

6. In a machine of the character described, the combination of a main frame provided with a track section, a ditch track section hinged to one end of said main frame and shaped to conform substantially to the cross-sectional profile of the trench to be dug, means to vertically adjust the position of said ditch track section, a dumping track section hinged to the other end of said main frame and adapted to overhang the levee to be built, means to support the outer end of said dumping track section, one or more sharp-edged shovels adapted to travel on said track sections, and means to operate said shovel or shovels, substantially as described.

7. In a machine of the character described, the combination of a main frame provided with a track section, a ditch track section hinged to one end of said main frame and shaped to conform substantially to the cross-sectional profile of the trench to be dug, one or more arms hinged to the same end of said main frame, means to support the free end of said arm or arms, a guide pulley mounted on said arm or arms, a cable passing over said pulley and operatively connected to said ditch track section, means to actuate said cable whereby the position of said ditch track section may be adjusted, a dumping track section secured to the opposite end of said main frame and adapted to overhang the position to be occupied by the levee, said track sections forming a continuous trackway, one or more sharp-edged shovels adapted to travel on said track sections, and means to cause said shovel or shovels to travel on said track sections, substantially as described.

8. In a machine of the character described, the combination of a main frame provided with a track section, a ditch track section secured to one end of said main frame and adapted to overhang the position to be occupied by the trench to be dug, a dumping track section secured to the other end of said main frame and adapted to overhang the position to be occupied by the levee to be built, said track sections forming a continuous trackway, one or more sharp-edged shovels adapted to travel on said track sections, means to cause said shovel or shovels to travel on said track sections, and a shield below said main frame track section to prevent dirt spilling from the shovel upon the ground between the levee and trench, substantially as described.
